UNITED STATES PATENT OFFICE.

NIC KRUMP, OF CHICAGO, ILLINOIS.

AUTOMATICALLY-OPENING SWITCH.

Application filed December 26, 1922. Serial No. 608,944.

To all whom it may concern:

Be it known that I, NIC KRUMP, a citizen of the United States, and a resident of Chicago, in the county of Cook and State of Illinois, have invented certain new and useful Improvements in an Automatically-Opening Switch, of which the following, when taken in connection with the drawings accompanying and forming a part hereof, is a specification.

This invention relates to an automatically opening switch for suspended two rail tracks which extend from a building to outside thereof through a door or other opening which is, at times, closed by a sliding door.

Among the objects of the invention is to obtain a switch which will be automatically operated by said door, to open and permit the door to be closed; to obtain a switch of the character named which is simple in construction, containing few parts, easily installed, not liable to become broken or out of order; to obtain a switch which will, when open, be provided with means to prevent a trolley approaching the switch at the open end thereof from becoming de-railed; and to obtain a switch which is easily operated, manually, to close it.

In the drawings referred to Fig. 1 is a top plan view of the rails of the switch and of the rails approaching the switch, showing, in cross section, a vertical member at one end of the switch.

Fig. 2 is a side elevation of the switch and of the rails approaching it.

Fig. 3 is a plan view on line 3—3 of Fig. 2, viewed as indicated by arrows.

Fig. 4 is a view of the switch in an open position, on line 4—4 of Fig. 2, viewed as indicated by arrows.

Fig. 5 is a top plan view of the rails approaching the open end of the switch, and of associated parts, showing the wheels of a trolley on said rails.

Fig. 6 is an elevation of the several parts illustrated in Fig. 5.

Fig. 7 is a side elevation of members (also illustrated in Fig. 2), in position unlocking the switch from a closed position.

Fig. 8 is an end elevation of the several member which are illustrated in Fig. 7.

Fig. 9 is a side elevation of the unlocking

members of the switch, at the opposite end thereof from that which is illustrated in Figs. 7 and 8; and

Fig. 10 is a top plan view of the several parts which are illustrated in Fig. 7, showing the cable by which the switch is opened when unlocked from its closed position.

A reference character applied to designate a given part indicates said part throughout the several figures of the drawings wherever the same appears.

A, A' represents suspended rails approaching the switch at the pivoted end thereof, and B, B', rails approaching said switch at the opposite end. X, X', Y, Y', indicate trolley wheels on said rails. C represents a chair which is arranged to support the ends of rails A, A', and also the pivoted end of the switch; and D represents a chair at the opposite end of the switch, which supports said end when the switch is closed, and also supports the ends of rails B, B'. E, E', represent the tracks of the switch, which consist, as represented, of a single rail which is bent, (as at e), so that the remainder of the rail forms parallel tracks or rails. The ends of the rails A, A' are bevelled to correspond with the bend e adjacent thereto. F represents a slot in chair C, and G a vertically extending bolt which is movable longitudinally in said slot. H, h, represents a combined standard and base, (illustrated as integral). The bolt G is secured in the lower end of standard and base H h, and g represents a washer on bolt G, between the head of said bolt and the under side of chair C. Base h is illustrated as resting on the flanges of rails E, E', and as firmly secured to said flanges by bar I, bolt i and nut i'. J J, represent pulleys which are loosely mounted on the upper end of standard H, in a horizontal plane, and resting on the table or plate H', which is rigidly secured on said standard. h' represents a bolt which is rigidly secured in plate H', and j represents a curved slot in pulleys J, J, in which said bolt h' may move when said pulleys are turned on standard H, said turning being limited by the length of said slot. By the foregoing described arrangement a rotatory movement of the pulleys J J, may occur before the rotation of the pulleys produces corresponding rotation of the standard H, base

h and the rails *E*, *E'*, forming the switch. *j* represents a hub to the upper one of the pulleys *J J*, and *K* represents an arm which is secured to hub *j*. *j', j'*, represents projections on the lower one of pulleys *J J*, and *k* represents a roller which is rotatably mounted between the projections *j', j'*. *L* represents a bell crank lever which is pivotally mounted at *l* on projection *L'* of standard 10 *H*. The upper edge of the horizontal member of bell crank *L* is in the path of movement of pulley *k* when the lever *K* and pulleys *J J*, are turned on standard *H*, as by a sliding door coming in contact with said lever, and thereby said pulley *k* is forced on to said horizontal member of the bell crank to force said horizontal member down and turn the bell crank on its pivot. The lower end of the vertical member of the bell crank is 15 thereby moved towards the right, as viewed in Fig. 2, and to said lower end is attached the rod *M*, which is, at its other end connected to bolt *m*. The bolt *m* is longitudinally movable in abutment *m'* of base *M'*. 20 The normal position of bolt *m* is illustrated in Fig. 2, in which position it is yeldingly held by spring *m''*. When said bolt is in said normal position the forward end thereof is in a recess provided therefor in standard 25 *N* on chair *D*. Said bolt therefore normally holds the switch closed, and until by the foregoing described angular movement of lever *K* and pulleys *J J*, the pulley *k* is forced on to bell crank *L*, to turn said bell crank on its 30 pivot, to release the switch from its locked condition, whereupon the switch is automatically opened by the means about to be described. *O* represents a standard which is secured on base *M'*, and *O'* is a cable or cord 35 which is attached to said standard and extended to and over the pulley *O''* and to the weight *O'''*. (see Fig. 10). *P* represents a standard which is rotatably mounted on chair *D*, and is provided with the horizontal 40 member *p* at its upper end. *P'* represents a forked member which is also mounted on standard *P*, and *p'* is the recess in said forked member. When the switch is closed the standard *O* is in recess *p'*, and the horizontal member *p* is between and parallel to the rails of the track, so that a trolley may 45 travel along said track. As the switch is opened the standard, or bolt *O* passes out of recess *p'*, and in so doing turns standard *p* approximately an angular distance of 50 ninety degrees, thereby turning horizontal member *p* at right angles to the tracks, causing said member to be an obstruction preventing a trolley to travel into the space left 55 open by the opening of the switch. (see Figs. 5 and 6). *p''*, Fig. 5, represents a stop to limit the turning of the standard *P*, as the standard or bolt *O* leaves the recess *p'*, in forked member *P'*. *Q* represents a cable or cord which extends around the pulleys *J J*, 60

and to a position where it may be grasped to manually turn the switch from an open to a closed position. *R* represents a rod by means of which the chair *C* is supported, and *R'* a rod by means of which chair *D* is 70 supported.

In the opening of the switch the side of rail *E* is forced against the end of rail *A* and thereby the base member *h* is forced outward, to move the bolt *G* longitudinally 75 in slot *F*, and when the switch is closed by means of cable or cord *Q* said base and the curved end *e* of the switch rail is drawn back to close contact with the ends of rails *A*, *A'*. When the switch is closed the bolt *m* 80 automatically locks it in a closed position.

I claim:

1. In an automatically opening switch, means to lock said switch in a closed position, in combination with means to unlock 85 said switch by the movement of a door, said means to unlock comprising a lever in the path of movement of said door, and means to automatically open said switch when unlocked. 90

2. In an automatically opening switch, a bolt arranged to be yeldingly held in a normal position to lock said switch in a closed position, means to retract said spring and unlock said switch, said unlocking means 95 comprising a standard, pulleys loosely mounted on said standard, means to limit the angular movement of said pulleys on said standard, a lever extending into the path of movement of a door, in combination 100 with a bell crank pivotally mounted on said standard and attached to the locking bolt, one member of said bell crank in the path of movement of said pulleys, and means to manually close said switch. 105

3. In an automatically opening switch, a bolt yeldingly held in a normal position to lock said switch in a closed position, means to retract said bolt to unlock said switch said means to retract comprising a standard 110 a pulley loosely mounted on said standard, means to limit the angular movement of said pulley on said standard, a lever rigidly attached to said pulley and extending into the path of movement of a door, a bell crank pivotally mounted adjacent to the end of one of its members and on said standard, a member on said pulley arranged to move onto the pivoted member 115 of said bell crank by the limited angular movement of said pulley, and a connection between said bell crank and said locking bolt, in combination with a cable extending around said pulley, a standard at the free end of said switch, a weight, and a cable 120 from said standard to said weight. 125

4. In an automatically opening switch, a standard at the free end of said switch, in combination with a rotatable standard provided with a horizontal member positioned 130

between the rails adjacent to said free end of said switch, and provided with a forked member, said standard on said switch arranged to leave and enter the recess formed by the fork of said forked member as said switch opens and closes, to turn said horizontal member into and out of position ob-

structing said rails adjacent to said free end of the switch.

NIC KRUMP.

In the presence of—

CHARLES TURNER BROWN,
B. S. BROWN.
